DESIGN FOR A WINDOW-SHADE.

Design No. 12,956, dated June 6, 1882.

UNITED STATES PATENT OFFICE.

BENJAMIN HANDFORTH, OF HOBOKEN, NEW JERSEY, AND ALONZO E. WEMPLE, OF BROOKLYN, NEW YORK.

DESIGN FOR A WINDOW-SHADE.

SPECIFICATION forming part of Design No. 12,956, dated June 6, 1882.

Application filed April 8, 1882. Term of patent 7 years.

To all whom it may concern:

Be it known that we, BENJAMIN HANDFORTH, of Hoboken, in the county of Hudson and State of New Jersey, and ALONZO E. WEMPLE, of Brooklyn, in the county of Kings and State of New York, have invented a Design for Window-Shades, of which the following is a specification.

The nature of our design is fully represented in the accompanying photographic illustration, to which reference is made.

A and B represent vertical stripes of different colors, which form the field or ground, which is partially and indiscriminately covered by open scroll-work C in such a manner that the field or ground of the two colors is seen between the lines forming the decoration; also an ornamental stripe, D, across the shade near the bottom, known to the trade by the name "dado." We prefer to make the stripe A orange, the stripe B ecru, and the decoration C gold, while the dado is gold and black; but we do not consider the colors selected to be an essential element in our design.

We are aware that striped window-shades are not new; and we do not claim them.

We are also aware that window-shades decorated with scroll-work on a field of one color with ornamental stripe or dado across are not new; and this we do not claim.

What we claim as our invention is—

1. A design for a window-shade, which consists of a combination of a field composed of vertical stripes of two colors and an open scroll, C, partially and indiscriminately covering both the colors, substantially as described.

2. The combination of a field composed of vertical stripes partially and indiscriminately covered by an open scroll, C, and an ornamental stripe or dado across the shade near the bottom.
